(57) **CLAIM**

The ornamental design for a kayak hull, as shown and described.

DESCRIPTION

FIG. 1 is a perspective view of a kayak hull, showing my new design taken from the right; it being understood that the perspective view taken from the left is a mirror image thereof;

FIG. 2 is a top plan view of my new design;

FIG. 3 is a side elevation view of my new design;

FIG. 4 is a bottom plan view of my new design;

FIG. 5 is a front end view of my new design; and,

FIG. 6 is a rear end view of my new design.

The broken lines in FIGS. 1 and 2 represent the unclaimed interior of the kayak hull.
